WORKMAN'S TIME RECORDER

Paul Fehr, Zug, Switzerland, assignor to Landis & Gyr, A. G., Zug, Switzerland, a corporation of Switzerland

Application September 26, 1947, Serial No. 776,312
In Switzerland October 28, 1946

7 Claims. (Cl. 346—86)

1

The present invention relates to improvements in workman's time recorders and more particularly to mechanism in such recorders for making automatic adjustments to accord with the number of days in particular months.

Objects and advantages of the invention will be set forth in part hereinafter and in part will be obvious herefrom or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

In time recorders or apparatus for checking working time, devices are known for setting the check-card holder day by day, in which a card stop is brought at regular intervals of time, by means of control mechanism, into a highest or maximum position, after which, on actuating a pawl, the stop reverts to its original position. The check card thereby comes every day into a higher position relatively to the printing mechanism of the apparatus, and the return of the card stop is effected according to the wage period in use—for instance 7 or 14 days. If a monthly wage period is in use, the check card is printed on both sides. On one side there are 15 days for one motion of the card stop and on the other side, according to the number of days in the month concerned, for every motion of the stop there are 15 or 16 days, or 13 and 14 days (normal February and leap year). In accordance with this variable number of days, the card stop must be re-set by hand at the end of each month to the original position. This monthly adjustment of the apparatus is troublesome and wastes time, besides which it calls for special attention, as if the setting is forgotten, the check card will be wrongly printed as regards the times.

The object of the present invention is to eliminate this drawback and to provide a device for operating time check apparatus for the day by day setting of the stop for the check card, in which a driving device for the check card stop is automatically adjusted to accord with the number of days in the particular months of the year.

The accompanying drawing shows in diagram-

2

matic perspective view an illustrative example of the invention.

Of the working-time-check apparatus only what is necessary to elucidate the invention has been shown, viz. the time wheel 1, which is driven by clockwork and is assumed to make one revolution in 24 hours, and the holder 2 of the check card.

With a rider 3, which is inserted in accordance with a daily time for connection (e. g. midnight) on the time wheel 1, there coacts a feeler arm 4, the shaft 5 of which carries the fork 6 of an escapement mechanism 6, 7. A two-armed rotary member 7 of this escapement mechanism 10 is driven by a source of power, which is assumed to be a spring barrel 8, and is positively connected through bevel gears and a pinion 9 with the gear wheel 10 of a driving device. The gear wheel 10 is loosely rotatable on a stud shaft 12 15 which is rigidly attached to a frame plate 11 and carries a ratchet wheel 13 to rotate with the gear wheel. On the stud shaft 12 a second gear wheel 14 is loosely rotatable and it has a crank arm 15, on which is mounted a pawl 17 by means 20 of a friction bush 16. This pawl, with the pawl element 18, coacts with the ratchet wheel 13 and has a projection 19, arranged to abut a fixed stop 20 on the stud shaft 12, and has further an arm 21 carrying a pin 22. The gear wheel 14 of the 25 driving device has a lifting pin 23 and is operatively connected through gear wheels 24, 25 and a rack 26 with the check card holder 2.

On a stud shaft 27 on the frame plate 11 a disc or stepped abutment member 29 is freely rotatable and forms a rigid whole with a ratchet wheel 28. This disc 29 is provided on its periphery with steps or notches 30 and carries a slide 32, with an abutment edge 33, which can be adjusted radially thereon by screws 31. The disc 29 lies in the plane of motion of the arm 21 of the pawl 17 and the path of motion of the abutment edge 33 intersects that of the pin 22. On the disc 29 there is fitted a disc 34 bearing the months of the year inscribed in a circle. A ratchet detent wheel 35, which forms one piece with the ratchet wheel 28 and the disc 29 and which coacts with a pawl pivotally mounted on the frame plate, prevents these parts from 40 reversing.

In the diagram, the abutment edge 33 is axially offset relatively to the slide 32. The abutment edge 33 could, however, also be aligned with the slide 32 and in place of the pin 22 the arm 21 45 could be enlarged at its free end, so that this

enlargement would act in conjunction with the abutment edge 33.

With the ratchet wheel 28 a feed pawl 36 engages resiliently, and the latter is carried on a pivoted lever 37, which coacts with the lifting pin 23 and is mounted so as to be freely rotatable on the hollow shaft which connects together the parts 28, 29 and 35. In front of the disc 34 a pointer 38 is rigidly mounted on the stud shaft 21, and this pointer shows the monthly setting of the disc 29.

The feed pawl 36 is controlled by a finger or stop 39, which forms one arm of a bell crank lever 39, 40 and is carried on a stud shaft 41 rigidly attached to the frame plate 11. A spring 42 holds the bell crank lever 39, 40 with an aperture 43 in its arm 40 against a stop pin 44, i. e., in the position controlling the pawl 36.

The method of operation of the arrangement above described is as follows, it being assumed for the sake of example that the wage period in use is a monthly one:

In the position of the mechanism shown, it is assumed that an end-of-month shift has taken place. Accordingly the check card holder 2 is in its lowest position, and the lifting pin 23, through the pivoted lever 37 and the pawl 36, has fed forward the ratchet wheel 28 with the disc 29, and this position of the holder 2 is effected by the projection 19 on the pawl member 17 resting against the stop 20 and by the engagement of the pawl member 18 with the ratchet wheel 13.

The spring mechanism 8 is not acting, as the escapement 6, 7 is locked and the feeler arm 4 is free from the rider 3 and so the gear wheel 10 is stationary. When in the course of rotation of the time wheel 1 the rider 3 raises the arm 4, the rotary member 7 of the escapement is released and the spring mechanism 8 turns the gear wheel 10, and its ratchet wheel 13 carries along the gear wheel 14 through the pawl member 17 and this lifts the card holder 2 through the gear wheels 24, 25. The rotary member 7 is, however, only released for half a revolution, as the escapement mechanism 6, 7, which is of a well known type, immediately impedes its rotation once more, and the transmission in the gears is such that on this half rotation, the card holder 2 is raised by one day, according to the printing on the check card. After a further 24 hours, the rider 3 again releases the escapement mechanism 6, 7 and the driving device 10, 13, 17, 15, 14 raises the card holder by a further day in accordance with the printing on the check card.

During this daily lift of the card holder, the lifting pin 23 moves away from the end of the pivoted lever 37 so that a spring 45 fitted on the pivoted lever 37 can move these parts in a counterclockwise direction, until the pivoted lever 37 comes to rest at a stop 46 on the frame plate 11.

After the card holder 2 has been lifted for 15 days according to the printing on the check card, the arm 21 of the pawl member 17 strikes against the periphery of the disc 29, so that the pawl element 18 of the pawl member 17 is released from the ratchet wheel 13 and the card holder 2, its weight being supported by a spring 47 acting on the toothed wheel 24, reverts to its initial position. Towards the end of this falling movement, the lifting pin 23 strikes the pivoted lever 37 and turns it with the ratchet pawl 36, whereby the latter turns the ratchet wheel 28 with the disc 29 by one step. In this movement of the feed pawl 36, the stop 39 prevents the pawl from leaving the teeth of the ratchet wheel 28.

On the return motion of the parts 14, 15, 17 of the catch device, corresponding to the drop of the holder 2, the pawl member 17 remains in the released position owing to the friction bush 16, i. e., it cannot fly out, and at the conclusion of the movement of the pawl 17 its projection 19 strikes against the stop 20, the result of which is the re-engagement of the pawl element 18 with the ratchet wheel 13, so that when the escapement mechanism 6, 7 is next released by the rider 3 the lift of the card holder 2 commences for the second half of the month. If the month happens to have 31 days, as assumed in the drawing, a notch 30 of the disc 29 lies in the path of motion of the arm 21 of the pawl element 17, and the arm 21 only rises after a further day, as in the previously described daily motion of the card holder 2, i. e., after 16 days on the bases of the notch 30, and effects the release of parts 13, 18 of the driving device and the drop of the card holder 2 into its initial position.

The further forward movement of the disc 29 brought about in this drop by the parts 36, 37, again brings part of the periphery of the disc into the path of movement of the arm 21 of the pawl member 17, so that in the next shifting cycle of the card holder 2, again corresponding to the first half of a month, the card holder is again raised up to the 15th day.

In the month of February, for this first part, the resetting of the holder 2 is effected as for the other months after the 15th day, but in the cycle of the second half of the month, the pin 22 strikes the abutment edge 33 of the slide 32, and the latter, for years in which February has the normal number of days, is set so that the abutment edge 33 projects beyond the periphery of the disc 29, so that the release of 17 and 18 is accomplished after the 13th day of the second half of the month, i. e., at the end of the 28th day of the month. For leap years, the slide 32 is set so that release takes place after the 14th day of the second half of the month of February, i. e., at the end of the 29th day.

According to the invention described, monthly interference with the apparatus for guiding the card holder correctly is no longer necessary, and control is carried out automatically after a single long term setting.

On putting the apparatus into service, in order to be able to set the monthly disc 29, the arm 40 is moved against the action of spring 42, whereby the pawl 36 is released from the stop 39.

The invention in its broader aspects is not limited to the specific mechanisms shown and described but departures may be made therefrom, within the scope of the accompanying claims, without departing from the principles of the invention and without sacrificing its chief advantages.

What I claim is:

1. A workman's time recorder comprising a card holder, means for periodically moving said holder away from an original position and means cooperating with said first means for periodically permitting the return of said holder to its original position, said first means including a pawl and ratchet wheel drive and said second means including a stepped abutment member having steps corresponding to the number of calendar days in individual months, arranged in the path of said pawl to be engaged thereby and disengage the pawl from the ratchet wheel, whereby said holder is permitted to return to its original position.

2. A workman's time recorder as claimed in

claim 1 in which said stepped abutment has fixed abutment steps corresponding to the fixed differences between the number of days of certain months and an adjustable abutment step corresponding to the month of February.

3. A workman's time recorder as claimed in claim 1 in which the stepped abutment member comprises a circular element having a notched periphery and an adjustable element having an abutment edge axially displaced from the plane of the said circular element and the said pawl carries an extension engageable with said adjustable element.

4. A workman's time recorder as claimed in claim 1 in which said moving means also includes a pair of gear wheels one of which carries said ratchet wheel and the other of which carries said pawl, a fixed stop to engage said pawl with said ratchet wheel upon the return of the card holder to its original position, pawl and ratchet wheel means for changing the position of said stepped abutment member and a projection upon the pawl carrying gear wheel to actuate said last pawl and ratchet wheel means.

5. A workman's time recorder as claimed in claim 4 in which the first mentioned pawl is mounted by a friction bush upon its gear wheel whereby upon disengagement from its ratchet

wheel by said stepped abutment member it remains disengaged until reengaged by said fixed stop.

6. A workman's time recorder as claimed in claim 5 in which a spring pressed finger engages the pawl urging it toward engagement with the ratchet wheel in the means for changing the position of the stepped abutment member.

7. A workman's time recorder as claimed in claim 6 in which the finger is laterally movable out of engagement with the pawl whereby said stepped abutment member may be changed as to position free of said pawl and ratchet wheel means.
